(57) **CLAIM**

The ornamental design for a shoe boot, as shown.

DESCRIPTION

FIG. 1 is a perspective view of a shoe boot, showing my new design.

FIG. 2 is a front view thereof.

FIG. 3 is a perspective right side view thereof.

FIG. 4 is a perspective rear view thereof.

FIG. 5 is a perspective bottom view thereof.

FIG. 6 is a right side view thereof in an alternate position; and,

FIG. 7 is a left side view thereof in an alternate position.
The surfaces of the shoe boot that are not shown form no part
of the claimed design.
